UNITED STATES PATENT OFFICE.

WILLIAM J. TINSLEY, OF WOODHAVEN, NEW YORK.

PRINTER'S QUOIN.

1,271,807.

Specification of Letters Patent. Patented July 9, 1918.

Application filed April 12, 1918. Serial No. 228,097.

To all whom it may concern:

Be it known that I, WILLIAM J. TINSLEY, a citizen of the United States, residing at Woodhaven, L. I., in the county of Queens 5 and State of New York, have invented new and useful Improvements in Printers' Quoins, of which the following is a specification.

This invention relates to printers' quoins 10 or locks adapted to be employed for locking up type forms.

As is well known, it frequently happens that the space between the type form and the chase, or between an inserted block, cut, 15 electrotype and the like and the body of type with which the same is associated is so small as to render it impossible to use the ordinary form of quoin, so that the type form, or the inserted cut is usually, under such conditions, secured or locked up by thin strips of 20 wood or pieces of thin leads, and in connection with these small pegs made from match stems or small pieces of wood, oftentimes employed as wedges in the locking-up operation.

One of the objects of the present invention is to eliminate this disadvantage by forming the quoin or lock of a pair of thin strip-like sections, each having wedging portions 30 adapted to coöperate to firmly and securely lock up the type form or cut.

Another object of the invention is the provision of a relatively long strip of material, preferably composed of metal, such as is 35 commonly employed in the manufacture of printers' leads and the like, and which strip is preferably formed with one flat side face, while the opposite face has a continuous wedge-shaped rib extending longitudinally 40 thereof throughout the length of the strip, said strip also being provided at intervals with suitable shaped notches. When furnished to the printer in this form, he may cut the strip into sections of the desired 45 lengths to form the quoins or locking members suitable in dimensions for the work on hand, the notches serving the purpose of permitting the use of a small hook-like tool for lifting or removing the device from its 50 wedging or locking relation with the type form.

It is also my purpose to provide a device of the character mentioned which will embody the desired device of simplicity, efficiency and convenience, which may be manufactured and marketed at a relatively low

cost, and which may be cut or trimmed by the printer to suit the requirements of the work in hand.

In the accompanying drawings:

Figure 1 is a perspective view of a strip from which the quoin or locking sections are intended to be cut as the printer may desire.

Fig. 2 is a similar view of a quoin or locking member cut from the strip.

Fig. 3 is a cross sectional view taken through associated quoin members just before being driven home.

Fig. 4 is a cross sectional view taken through a conventionally illustrated type form and showing a cut or block locked therein by my device.

Fig. 5 is a perspective view of an implement intended to be used in inserting and removing the quoin or locking members.

Referring now to the accompanying drawings in detail, and particularly to Fig. 1 thereof, the letter A indicates a strip of any desired and convenient length, say one to three feet. This strip is preferably formed 80 from metal which may be easily and readily cut or trimmed with an ordinary hand operated printer's cutter. One vertical side face of this strip, such as the face 1, is preferably made flat or straight, while the upper portion of the opposite side face 2 has a rib 3 extending longitudinally thereof throughout the entire length of the strip. The lower edge of this rib is beveled as at 4, so as to merge into the lower straight face section 5 of the strip at about the central longitudinal line of the latter, the result being that this lower section 5 of the face 2 is parallel with the face 1, while the upper section of this strip is thickened or enlarged by the rib and gradually merges or tapers into the lower section of such strip. It is also true, as will be understood by reference to Fig. 1, that the upper portion of the rib forming the 90 thickened section of the strip is preferably likewise made parallel with the opposite straight face 1 of the strip. Formed in the upper or ribbed section of the strip at suitably spaced intervals, are the key slots 6, 95 preferably shaped as shown to provide two shoulders 7 and 8. I prefer to form the slots of this shape, for the reason that in using the implement B shown in Fig. 5, the hook b of the latter may engage either of the 100 shoulders as may be convenient at the time, and furthermore, in cutting the strip, shown

in Fig. 1, up into sections C such as is shown in Fig. 2, it may happen that in order to obtain a section or member of the desired length, it will be necessary to sever the strip 5 in a line running vertically through one of the slots and under such conditions the severed strip will be provided with a hook-engaging shoulder at one end as shown at 9 in Fig. 2.

10 It is my intention that the printer shall be furnished with the long continuous strips, such as is shown in Fig. 1, so that when required, he may, by means of the ordinary hand operated cutting or trimming tool cut 15 from the strip a locking section or member of a desired and convenient length for the work at hand, one of such severed members or sections being shown in Fig. 2. In this instance it will be noted that one of the key 20 slots 6 appears intermediate the length of the section; while as above described, in the cutting of the strip, the cut has been made through another of the key slots so that the hook-engaging shoulder 9 appears at one 25 end of the section or member.

The manner of using the device will be readily understood by reference to Figs. 3 and 4. In Fig. 4, the letter D designates a printing plate base upon which is mounted 30 the usual printing plate E. This base, as well as the plate, has an opening F therein for the insertion of the small block G which may be an electrotype block, cut or other printing element. To fasten this insert 35 block or cut G in position, I may employ at one side thereof the usual furniture indicated at H, while at the opposite side of the block, or in the relatively narrow space between the base of the insert block and the 40 base of the printing plate, I arrange a co-operating pair of my locking or quoin members, these being positioned relatively to each other, as shown in Fig. 3, that is to say are disposed opposite to each other and in 45 sliding contact. The edge b' of the tool B, which is preferably of slightly less dimensions than the thickened or rib portion of the locking or quoin member may now be placed against the top edge of the uppermost member and by sharp blows with any 50 suitable instrument, the upper member may be driven home or into the position shown in Fig. 4. It will be noticed, of course, that the lower thinned portion of the upper member will move downward and be directed outward by the beveled edge 4 of the rib of the lower member during the tamping operation, so that this thinned portion 55 of the upper member will be directed between the thickened portion of the lower member and the adjacent wall section of the base D, with the result that the insert block 60 will be wedged or locked firmly in position. In other words, the locking or wedging action of the two members is brought about 65

by causing a relatively vertical movement between the same, as contradistinguished from the ordinary form of quoin, wherein the locking action takes place by sliding or shifting the wedge-shaped quoin members 70 lengthwise and horizontally relative to each other. As my locking quoin is vertically expandable, instead of laterally expansible, the locking members may be inserted and used in short, narrow spaces in the type form, 75 where it would be impossible to employ the ordinary quoins because there would not be room enough to accommodate such quoins when laterally extended by moving the same horizontally relative to each other to obtain 80 the necessary wedging action. Of course, when the two locking or quoin sections are in position as shown in Fig. 4, their height is less than the height of the printing plate and its base so that these members will lie 85 below the level of the printing section of the plate. It will be also noted that it will be impossible for the members to work up toward the printing face of the plate after they have been driven home into locking re 90 lation and the consequent liability of the locking members printing upon or marring the paper is avoided. When it is desired to take out the locking members so as to permit the removal of the insert block, it is 95 only necessary to insert the tool B beneath one of the notched shoulders in the upper member and pull toward to draw such member above the printing face or into position to be grasped and removed. Of course, 100 it will be understood that any suitable tool or device may be employed for lifting or removing the locking or quoin members, the implement B shown herein being merely one convenient means for this purpose. 105

It will further be understood that the invention may be embodied in the form of quads to be employed as such devices are ordinarily used in the printing art.

While I have herein shown and described 110 one particular embodiment of my invention, I wish to be understood that I do not limit myself to the precise details herein set forth by way of illustration, as modification and variation may be made without departing 115 from the spirit of the invention or exceeding the scope of the appended claims.

What I claim is:

1. A device for use as a printer's quoin or lock comprising a pair of substantially flat 120 strip-like members, each having a thickened or rib portion extending longitudinally thereof, said members being disposed opposite to each other and in cooperative contact, one of said members being movable vertically relative to the other to bring the members into locking position.

2. A device for use as a printer's quoin or lock comprising a pair of strip-like members, each having a straight, flat face at one side, 130

- while the opposite side is provided with a longitudinally extending rib forming a thickened portion for the member, said rib having a straight section extending parallel 5 to the afore-mentioned flat face, and a beveled edge merging into the face upon which the rib is located, said members being disposed opposite to each other and in cooperative engagement when in locking position.
- 10 3. A printer's quoin or locking member comprising a strip-like section having a straight, flat face at one side, the opposite side of said member having a rib extending longitudinally thereof and forming a thickened section on the member, said rib having a straight, flat portion extending parallel to the first mentioned straight, flat face and having a longitudinally extending beveled portion merging into the face upon which 15 the rib is located.
4. A printer's quoin or locking member comprising a flat strip adapted to be vertically disposed to present top and bottom edges and opposing vertical sides when in 20 type-locking position, said opposing sides having parallel face sections, and a rib extending longitudinally of such a face section of one of the vertical sides.
5. A printer's quoin or locking member comprising a strip-like section having opposing parallel side portions and having a beveled rib extending longitudinally of one 25 of said side portions.
6. A device for use as a printer's quoin or locking member comprising a strip-like sec- 35 tion having opposing parallel, vertical side portions and having a beveled rib extending longitudinally of one of said side portions thereof, said strip being provided with tool-engaging means. 40
7. A printer's quoin or locking member comprising a strip having a thickened portion formed with opposing parallel side faces and a beveled section extending longitudinally of one of said faces and having 45 a tool-engaging shoulder.
8. A printer's quoin or locking member comprising a strip having parallel, vertical side faces, and a rib extending longitudinally of one of the side faces and forming a 50 thickened portion for the strip, said rib having a beveled portion, the thickened section of said strip having a notch formed therein to provide a tool-engaging shoulder.
9. A strip for making printer's quoins or 55 locking member comprising a relatively long strip-like member having a thickened beveled portion extending longitudinally at one face thereof and having a series of notches placed along one edge thereof and forming 60 tool-engaging shoulders, said strip being adapted to be subdivided into sections of selected sizes, to provide locking or quoin members.

In testimony whereof I have hereunto set 65 my hand.

WILLIAM J. TINSLEY.
